LEVI KITTINGER, OF MASSILLON, OHIO.

Letters Patent No. 86,233, dated January 26, 1869.

IMPROVEMENT IN LOOM FOR WEAVING WIRE CLOTH.

The Schedule referred to in these Letters Patent and making part of the same.

To all whom it may concern:

Be it known that I, LEVI KITTINGER, of Massillon, in the county of Stark, and State of Ohio, have invented new and useful Improvements in Wire-Weaving Looms; and I do hereby declare that the following is a full, clear, and exact description of my invention, reference being had to the accompanying drawings, forming a part of this specification, and to the letters of reference marked thereon, of which drawings—

Figure 1 is an elevation of my improved loom.

Figure 2 is a plan of the same.

Figures 3 are elevation and plan of shuttle.

Figure 4 is a cross-section of shuttle-spool.

Figure 5 is a detailed elevation of mechanism for operating the shuttle.

Figure 6 is an end view of the same.

Figures 7 are detailed views of shuttle-bars.

Figure 8 is a detailed view of mechanism for operating the harness.

Figure 9 is a detailed view of mechanism for operating the filling-presser.

Figure 10 is a front view of filling-presser.

Figure 11 is a sectional detailed view of the drawing and receiving-rollers, with their accompanying mechanism.

Figures 12 are elevation and plan of one of the friction-ratchets.

Figures 13 are section and plan of mesh-former.

My invention relates to certain improvements in looms for weaving wire cloth; said improvements consisting in the novel mode of constructing the shuttle-spool, whereby it is made very easy to put into or take out of the shuttle, and has also the advantage of preventing wire on the spool from unwinding, by reason of its elasticity; also, in the novel mode of operating the shuttle; also, in the novel construction and operation of a mesh-former, whereby I obtain a cloth with all its meshes of precisely the same shape and size; also, in the construction of a filling-presser, which acts, in combination with the mesh-former, to aid in the obtaining of a perfect mesh; also, in the novel mode of operating said filling-presser; also, in the novel mechanism for operating the harness which operates the wires which constitute the warp of the cloth; and, lastly, in the novel mode of regulating the rolling up of the cloth after it has been woven.

The peculiar utility of these several improvements consists in the making of a cloth with all its meshes of precisely the same form and size, and having all the wires of which it is composed free from any kinks or irregularities; also, in making a superior article of merchandise at a more rapid rate, and hence, at an expense less than that of making an inferior article on looms heretofore used for this purpose.

To enable others skilled in the art to make and use my invention, I will proceed to describe its construction and operation.

B B are the main sills of the machine, on which are secured the lower frame-pieces A A.

In these frame-pieces are secured the uprights C C and E E, which have upper frame-pieces F F secured to them, as shown.

The cross-pieces H and J connect the upper frame-pieces F F, and outside cross-pieces G G and M M (see fig. 5) connect the outer uprights D D to the main frame, the upright, D', being arranged between the pieces G and M, as shown.

The main driving-shaft L has its bearings in boxes 22, 22 on the lower frame-pieces A A, and power is communicated to said shaft by means of the pulley 54, or in any other suitable manner.

The warp-wire drum 56 is hung in boxes 82, 82 on the uprights E E.

At the end of the frame, and on one end of its axis 83, is secured the gear-wheel 59, which gears into a second gear-wheel, 60, which is secured to the axis 84 of the friction-wheel 61.

This axis 84 runs in a box on the upright, E, (not seen in drawings,) and in a hole in the upright, 85, attached to the piece A.

Around the friction-wheel 61 is placed a belt, 62, which is secured, at one end, to a hook, 64, in the arm 86, which is of the form shown in figs. 1 and 2, and is secured to the sill B, while the other end of said belt 62 is attached to a sliding collar, 63, which works up and down on the screw-bolt 65.

A spiral spring is arranged on the bolt 65, as seen in fig. 1, its upper end bearing on a collar on said bolt, while the lower end bears on the sliding collar 63.

A thumb-nut, 67, is arranged on the bolt 65, below the arm 86, and the bolt 65 is made so as to slide in holes made in the upper and lower horizontal parts of the arm 86.

It is readily seen that, by screwing up or unscrewing the nut 67, the friction of the belt 62 on the wheel 61 may be varied at pleasure, thereby regulating the rotation of the drum 56, and consequently the tension on the warp-wires.

On the warp-wire drum are arranged the disks 57, 57, which are thin rings of metal, arranged perpendicularly to the axis of said drum, and which divide the surface of said drum into several parts, on which the different warp-wires are wound, the object being to keep each wire separate from the others, to prevent any tangling of said wires.

The warp-wires pass from the drum 56 up over the roller 58, arranged on the end of uprights E E, as shown, and from here, through the loops 87, 87 in the harness N and O, the same as the warp-threads in the common loom. They are then passed through the spaces between the bars 13, 13 of the filling-presses 11, (see fig. 10,) and from thence pass between the mesh-blocks 51, 51 of the mesh-former 50, (see figs. 1 and 2.) Beyond these mesh-blocks they form a part of the woven cloth.

which passes over the roller 28, and around between said roller and the roller 27, thence over said roller 27 on to the receiving-roller 15.

The position of the warp-wires, from the warp-wire drum 56, to the mesh-former 50, is shown by blue lines in figs. 1 and 2, while the movement of the woven cloth from the mesh-former on to the receiving-roller 15, is shown by blue lines in fig. 11.

The shuttle *n* is of the form shown in figs. 3, and has a hole, *o*, with slots *o' o'* made in each side.

This shuttle is operated by the shuttle-bars *b b*, which have the pointed ends *b' b'*, with wings *b' b'*, of the same size as the hole *o*, and slots *o' o'* in the shuttle, so that said ends *b' b'* pass through the holes *o* in the shuttle, and support the same, as seen in figs. 1 and 2.

These shuttle-bars *b b* are of peculiar construction, being made of a tube, *b*, having a flange, *b'*, on its lower side, and a rod, *b'*, inside the tube *b*, as shown in fig. 7.

The head *b'* is arranged on the rod *b'*, and the end 79 of the tube *b* is of the same shape and size as the head *b'*, up to the collar *b'*, the distance from rear of head *b'* to collar *b'* being equal to the length of one of the holes *o* in the sides of the shuttle *n*, from which it is readily seen that the end of the rod and tube *b' b* may be introduced into the hole *o* of the shuttle *n*, and the shuttle be then secured in that position, by simply turning the rod *b'*, so as to bring the wings *b' b'* out of line with the slots *o' o'* of the hole *o*, as seen in fig. 2.

The shuttle-bars *b b* are arranged to slide in the supports *p p*, which are attached to the pieces *G G* and *D D* of the frame, and are caused to slide in said supports by the links *q q*, which are attached to the flanges *b'*, as seen in fig. 5, their other ends being secured to the arms *r r* of the rock-levers *t t*, which are secured on the rock-shafts *t' t'*, said rock-shafts being hung in boxes *r' r'* on the frame-piece *A*, as shown by small detached plan in fig. 5.

On the shaft *L* is arranged the centre arm *V*, which is made of the form shown in figs. 5 and 6, and the side arms *u u*, of the form there shown.

It is readily seen that by rotating the shaft *L*, the centre arm *V* will first strike the inner ends of the rock-levers *t t*, and force them down, as shown, thereby causing the rods *b b* to approach each other. Then, as soon as this arm *V* turns beyond the ends of the rock-levers *t t*, said levers are struck on their other ends by the side arms *u u*, and turned up at a contrary angle, thereby causing the rods *b b* to recede from each other.

The adjustable plates *3 3* are arranged on the ends of the levers *t*, to compensate for any wearing at said ends.

On the ends of the rods *b' b'* are arranged the wheels *c c*, having teeth arranged on their edges, and four notches, on lines at right angles to each other, on the raised rims or their faces.

An arm, *k*, of the form shown, is secured to the tube *b*, and has a spring, *j*, arranged as shown, the ends of said spring lying in the notches in the raised rim of the wheel *c*, thus preventing a rotation of the rod *b'*, except when the proper power is applied.

The slides *d d* are of the form shown, and are arranged to slide up and down on the outer uprights *D D*, by means of the slot *f*, which allows the movement over the bolts that secure them to the side of the uprights *D*, while their upper ends have a hole through which pass the rods *m m*, which are inserted in the top of the uprights *D*, and around which are placed spiral springs, which serve to raise the slides *d d*.

One or more pins, *e e*, are inserted in the slides *d d*, which engage with the teeth on the edge of the wheels *c c*, and cause a rotation of said wheels when the slides *d d* are forced down.

The arms *h h* are of the form shown, and are secured at the ends of the shaft *L* by bolts *t t*, which pass through slots *i i* in said arms, and screw into holes in the end of the shaft.

These arms *h h* are of such length that at each revolution

of the shaft *L*, they strike the projection *g g*, at the lower ends of the slides *d d*, and force said slides down.

From the foregoing description it is readily seen that when the several parts are properly adjusted, and the shuttle *n* is standing in the position shown in fig. 2, by revolving the shaft *L*, the action of the arm *V* will cause the bars *b b* to come together, and that both ends, *b' b'*, of the rods *b' b'*, will then be on the inside of the shuttle *n*, which will then be in the centre of the warp, as seen in fig. 5, while the wheels *c c* will be brought up against the slides *d d*. Then, while the bars *b b* and shuttle *n* are in this position, the arms *h h* strike the projections *g g* of the slides *d d*, and force said slides down, and by reason of the action of the pins *e e* on the teeth of the wheels *c c*, cause a quarter turn of said wheel, (the spring *j* sliding out of one notch, on the raised rim of the wheel *c*, and springing into the next notch, to allow of this quarter turn.) This causes a quarter turn of the heads *b' b'* on the rods *b' b'*, and therefore releases the shuttle *n* from the bar *b*, by which it was brought to the centre, and fastens it to the other arm *b*. As soon as this is done, the arms *u u*, by their action on the rock-levers *t t*, cause the bars *b b* to recede from the centre, as before shown.

The harness-frames *N* and *O* are of the general form shown in fig. 8, and have the loops 87, 87 arranged in them, in a similar manner to those of the harness in an ordinary loom.

These harness-frames are arranged to slide up and down in standards or guides 2, 2, attached to the frame-pieces *F F*.

The connecting-links on pitmen, *P* and *Q*, connect the harness *N* and *O* to the double-crank shaft *R*, by the revolution of which the harness are caused to move up and down.

This shaft *R* is hung in standards 55, 55, which are secured to the lower frame-pieces *A A*, and has the gear-wheel *S* secured at one end, which wheel gears into the wheel *T* on the shaft *U*.

This shaft *U* is hung in boxes *a a* on the uprights *D D*, as shown, and has secured to it the wheel *V*, which is a circular wheel, having four slots, 81, 81, arranged on its periphery, which are on lines at right angles to each other, and has also the pins 82, 82 arranged around at equal intervals on its face, in such a manner as to form a kind of lantern-wheel.

A standard-plate, *Y*, (see fig. 1,) is secured to the upright, *D*, and has its outer end turned at right angles to the main part, and provided with a hole, through which slides the upper end of the bar *X*, the lower part of which is flattened out, and provided with a slot, through which passes the shaft *U*, as seen in fig. 8.

A spiral spring is placed around the upper part of the bar *X*, and presses against the upper part of standard *Y*, thus serving to keep the pin 90, in the bar *X*, pressed into the slot 81 in wheel *V*.

The lower end of the bar *X* has the flat part turned up, as seen in fig. 8.

A segment of a plate gear-wheel, *W*, is secured on the main shaft *L*, in such position as to gear with the lantern-wheel *V* at each revolution of the main shaft, and has secured to it an arm, *Z*, which is so constructed and arranged as that it shall strike the lower end of the bar *X*, and cause the same to slide up, thereby drawing the pin 90 on the bar *X* from the slot 81 on the wheel *V*, before the segment *W* begins to act on the lantern-wheel *V*.

The segment *W* is of such size that, at each revolution of the main shaft *L*, it will cause a quarter revolution of the wheel *V*, and consequently of the wheel *T*. This wheel *T* is made of a diameter twice that of the wheel *S*; consequently, the quarter revolution of the wheel *T* causes a half revolution of the wheel *S* and of the crank-shaft *R*, thereby changing the harness *N* and *O*.

The notches 81, in the wheel *V*, are so arranged that

when the pin 90 is in one of the notches 81, the cranks of the shaft R shall be in a vertical position, shown in fig. 8, thereby securing the harness N and O, at the extremes of their movements, against any danger of being slid up or down by the tension on the warp-wires.

The mesh-former 50 is provided with an axis, which is hung in boxes 54, 54, on the upper frame-pieces F F, and consists of a plate, (see fig. 13,) having a mesh-plate, 91, with mesh-blocks 51, 51, of the size of the required mesh, arranged as shown, secured to it by one or more screws, 92.

At one end of the axis or shaft of the mesh-former is secured the crank 49, having a rod, 48, at its end, which connects with a lever, 46, that is pivoted to the frame-piece A, as seen in fig. 1.

A pin, 52, is so arranged on the shaft L that, at each revolution of said shaft, and at the instant the row of meshes is formed, it shall strike the lever 46, and force it down, and, through the action of the rod 48 and crank 49, turn down the mesh-former 50, so that the cloth may be drawn along by the drawing or take-up rollers, the length of one mesh, and the thickness of one filling-wire, when the pin 52 slips from the lever 46, and the mesh-former 50 is turned to its working-position, by the action of the spiral spring 68, which is attached to the lever 46 and to the upright, c.

The filling-presser 11 is of the form shown in fig. 10, having the bars 13, 13, which form the face of the presser, and which have spaces between them, through which pass the warp-wires.

This presser has the slides 14, 14 at the sides, which slide in guides 12, 12, on the frame-pieces F F, and has the arms 6, 6 pivoted at the sides, which are connected at their ends to the arms 5, 5 of the rock-shaft 93. This rock-shaft is hung in boxes or standards 94, 94, on the frame-pieces A A, and has an arm, 4, with an adjustable plate, 7, (shown in detached plan,) secured at its end by means of a screw, as shown.

Another arm, 8, is also secured to the rock-shaft 93, which has the link 9 connected to its outer end, by which it is connected to the lever 10, which is pivoted to the sill B, as shown.

An arm, w, is so arranged on the main shaft L, that, at each revolution of said shaft, the arm w will first strike the plate 7, thereby forcing down the arm 4, and causing a forward movement of the presser 11, through the action of the shaft 93 and arms 5 and 6.

This movement of the presser 11 is arranged so as to take place as soon as the shuttle has been carried through the warp-wires, and by such action has laid the filling-wire at the face of the mesh-blocks 51, when it is readily seen that the presser 11, coming up against the mesh-blocks 51, 51, will press the filling-wire squarely up against said blocks, thereby making a more perfect mesh.

The forward movement of the presser 11 is regulated to suit the different sizes of mesh-blocks, by means of the adjustable plate 7, in a manner readily seen, and the backward movement of the presser is effected by the arm w, of the main shaft L, striking the face of the lever 10, after leaving the plate 7, (said lever 10 having been raised by the forcing down of the arm 4, through the action of arm 8 and link 9,) the forcing down of said lever 10 causing the backward movement of the presser, through the action of link 9, arm 8, shaft 93, and arms 5 and 6, in a manner too evident to require explanation.

The drawing or take-up roller 28 is arranged in boxes on the frame-pieces F F, as shown, and has a gear-wheel, 29, secured to it at one end, which meshes into another gear-wheel, 30, on the other drawing-roller, 27.

This roller 27 is hung in boxes 31, 31, which slide on the bars 32, 32, which are secured to the pieces F F and C C of the frame, (see fig. 11,) and the screws 33, 33 are arranged in the pieces C C, so as to press against

the boxes 31, 31, and serve to regulate the distance between the rollers 28 and 27 to the kind of cloth being woven.

The gear-wheel 38 (see figs. 1 and 2) is arranged on one end of the axis of the roller 28, and meshes into the gear-wheel 39, which is screwed to a shaft, 26, (see fig. 11,) which runs in standards 25, 25, secured to the frame-pieces F F and C C.

On this shaft 26 is also secured a friction-wheel, 40, and a friction-pawl, 41, is hung, by a spiral spring, 45, secured to it and to the shaft of the mesh-former, or to the frame C C, if preferred, in such a manner as to act on the wheel 40 with a ratchet-motion.

The slot 42 is made in the arm of friction-pawl 41, and a bolt, 96, passes through said slot, and secures the rod 43 to the friction-pawl 41.

This rod 43 is fastened, at the lower end, to a lever, 44, which is pivoted to the sill B, as seen in fig. 1.

A pin, 53, is arranged on the main shaft L, so that, at each revolution of said shaft, the pin 53 strikes the lever 44, forces it down, and, through the action of rod 43, draws down the pawl 41, and thereby causes a rotation of the wheel 40, which causes a forward or take-up motion of the cloth, through the action of the gear-wheels 38 and 39 and rollers 28 and 27, with their connecting gear-wheels 29 and 30.

The amount of take-up motion for the cloth is regulated by moving the bolt 96 forward or backward in the slot 42 in the pawl 41.

A second friction-clutch stop-ratchet, 37, is attached to the wheel 40, and to the upright, C, by a spring, 69, and has its arm projecting through a slotted plate, 47, on the frame-piece A, the object of this clutch being to prevent any backward movement of the wheel 40, and, consequently, of the drawing-rollers 27 and 28, during the upward or backward motion of the pawl 41.

This receiving-roller 15, on which the cloth is wound, is hung, by suitable axis, in standards, 99, 99, on the frame-pieces A A, and has a friction-wheel, 16, secured to it at each end.

A friction-pawl, 17, is arranged to act on each of these wheels, 16, 16, the said pawls being suspended by spiral springs 23, 23, fig. 11, which are attached to arms 24, 24, on the uprights C C.

The ends of these pawls 17, 17, extend to the main shaft L, and have pivoted to them the rods 18, 18, around which are placed the spiral springs 20, 20, the upper ends of said rods working up through holes in the support 19, of the form shown in fig. 11, said supports 19 being secured to pieces I I, which pass from the cross-piece H, near one end of frame, to cross-piece J, near the other end. (See fig. 2.) Two arms, 21, 21, (one of which is seen in fig. 11,) are inserted in the shaft L, one under each ratchet, 17, and at an angular distance of ninety or one hundred and eighty degrees from each other, so that at each revolution of the main shaft an arm, 21, strikes the end of ratchet 17, thereby raising the same, and the spring 20 forcing down said ratchet and winding up the cloth. The arm 21 and ratchet 17, on the other side, operate in a similar manner, and the cloth is kept constantly wound up, and no slack cloth is allowed to accumulate between the drawing-rollers and feed-rollers.

The general construction and operation of the friction-wheels and friction-pawls are shown in figs. 12, and are too obvious to require special description.

The tension-device for the shuttle n consists of a cone-shaped device, 70, having a screw-thread, 71, (of a size depending on the size of the filling-wire, and of a pitch depending on the tension required on said wire,) cut in its outer surface, and is arranged on the base 80, said base being hollow, and having a pin, 98, passing through it and the sides of the shuttle, by which the cone 70 may be turned up at right angles to the body of the shuttle.

When in this position, the filling-wire is wound into

the thread 71, and the end of the wire is put through a hole, 77, in the end of the shuttle, when the cone 70 is turned down into the position shown in figs. 3, and the shuttle is ready for operation.

The mouth of hole 77 in the shuttle is rounded horizontally, as indicated by dotted lines in fig. 3, so as not to cut or kink the filling-wire.

The filling-spool 72 is of the form shown in fig. 4, and has a pin or axis, 75, at one end, and hole, 74, with a pin, 76, therein, which projects beyond the end of the spool, and forms a pin or axis for the other end of the spool.

A collar, 73, is placed over the pin 76, and has within it the spiral spring 97.

It is readily seen that by pressing down the collar 73 until its top is flush with the end of the spool, said spool can readily be inserted in the shuttle *n*, as seen in figs. 3, and that when so inserted, it will be retained in that position, and be prevented from recoiling by the elasticity of the filling-wire, by reason of the action of the spring 97 on the collar 73.

It is evident that, instead of using the flange *b*² on the tube *b*, a slot cut in the tube may be used, the bearings *p p*, in this case, having projections or pins in their inner sides, which would slide in the slots in the tube *b*; the object of the flanges or slots in either case being to prevent the tube *b* from turning. Also, that slots could be used in the head *b*², and the tube *b*, instead of flanges *b*² *b*³, the holes *o o*, in the shuttle *n*, in this case having projections or pins *o o'*, instead of the slots *o o''*, as now shown.

Having thus fully described my invention,

What I claim as new, and desire to secure by Letters Patent, is—

1. The shuttle-spool 72 and its tension devices, the several parts being constructed and arranged in the manner and for the purpose specified.

2. The combination of tension-device 70, base 80, axial pin 98, and shuttle *n*, when said parts are so arranged as to allow of the turning up of the tension-device 70, substantially as herein specified.

3. The head *b*² on the bar *b*, when constructed and used substantially in the manner and for the purpose specified.

4. The shuttle-bar, composed of the tube *b*, with collar *b*² and flanges *b*² *b*³, or their equivalents, and the rod *b*⁴, in combination with shuttle *n*, when constructed substantially in the manner and for the purpose specified.

5. The combination of the tube *b*, arm *k*, spring *j*, wheel *c*, with edge-teeth, and raised, notched-face rim and rod *b*⁴, the several parts being arranged as and for the purpose herein specified.

6. The combination of the wheels *c c*, the slides *d d*, with one or more pins, *e*, springs *m m*, and main shaft *L*, with arms *h h* thereon, the several parts being arranged as and for the purpose herein specified.

7. The combination of the shuttle-bars *b b*, links *q q*,

arms *r r*, rock-levers *t t*, rock-shaft *t' t'*, and main shaft *L*, with arms *v v*, the several parts being arranged as and for the purpose specified.

8. The mesh-former; composed of the plate and axle 50, mesh-plate 91, with mesh-blocks 51, 51, and one or more connecting-screws, 92, the several parts being combined and arranged substantially in the manner and for the purpose specified.

9. The combination of the mesh-former with crank 49, rod 48, lever 46, spring 68, and main shaft *L*, with pin 52, the several parts being arranged substantially as and for the purpose specified.

10. The filling-presser 11, composed of a frame, with slides 14, 14, and bars 13, 13, when used in combination with the mesh-former, substantially in the manner and for the purpose specified.

11. The combination of the filling-presser 11, arms 6, 6, arms 5, 5, rock-shaft 93, arm 4, arm 8, link 9, lever 10, and main shaft *L*, with arm *w*, the several parts being arranged substantially as and for the purpose specified.

12. The adjustable plate 7, constructed as described, in combination with the arm 4 of the filling-presser, operating-mechanism, and the arm *w* of the main shaft *L*, substantially as and for the purpose specified.

13. The combination of the harness *N* and *O*, pit-men *P* and *Q*, double-crank shaft *R*, gear-wheels *S* and *T*, lantern-wheel *V*, with notches 81, 81, slide-bars *z*, with pin 90 and main shaft *L*, with gear-segment *W* and arm *Z*, the several parts being combined and arranged substantially as and for the purpose specified.

14. The combination of the roller 28 with gear-wheel 29, roller 27 with gear-wheels 30 and 38, sliding boxes 31, 31, and adjusting-screws 33, 33, gear-wheel 39, friction-wheel 40, and friction-pawl 41, the several parts being constructed and arranged substantially as and for the purpose specified.

15. The combination of the friction-pawl 41 with springs 45 and slot 42, the bolt 96, rod 43, lever 44, and main shaft *L* with arm 53, the several parts being constructed and arranged substantially as and for the purpose specified.

16. The clutch 37, with spring 69 and slotted plate 47, when used in combination with the friction-wheel 40, drawing-rollers 27 and 28, and pawl 41, substantially as and for the purpose herein specified.

17. The combination of the receiving-roller 15 with friction-wheels 16, 16, the pawls 17, 17, with springs 23 and 20, and the main shaft *L* with arms 21, 21, the several parts being constructed and arranged substantially as and for the purpose herein specified.

As evidence that I claim the foregoing, I have hereunto set my hand, in presence of two witnesses, this 29th day of June, A. D. 1868.

Witnesses:
